PORTABLE DITCH GATE

Harold A. Saunders and Carmen V. Saunders,
Denver, Colo., assignors to Midstate Manufacturing Company, Denver, Colo., a corporation of Colorado

Application May 2, 1949, Serial No. 90,916

2 Claims. (Cl. 61—29)

1

This invention relates to the control of flow of water in ditches and more particularly to a gate or dam therefor.

One of the objects of the invention is to produce an improved portable gate or dam for a ditch to thus permit control of the flow of water in the ditch for any desired purposes as, for example, lateral irrigation.

Another object is to provide an improved portable gate or dam for a ditch which will be adjustable in an easy and convenient manner to vary the height of the water which is to be dammed up in a ditch.

Still another object is to produce an improved sectional stick for use with impervious sheet material which will be so constructed as to permit adjustable gate or dam height, yet can be folded either with or without a dam sheet into a compact structure for transporting or storage.

Yet another object is to produce improved means for hinging sections of a portable gate or dam stick together and permit their angular adjustment to thereby establish varied dam heights when used to dam up water in ditches.

A further object is to so construct a metal stick that a sheet of impervious material used therewith for damming purposes can be firmly secured thereto in a manner permitting easy and quick attachment.

Other objects of our invention will become apparent from the following description taken in connection with the accompanying drawings in which:

Figure 1 is a perspective view of a ditch showing our improved portable ditch gate associated therewith to dam up and control the flow of water in the ditch for irrigation purposes;

Figure 2 is a sectional view taken on the line 2—2 of Figure 1 showing how the sheet material attached to the dam stick is held in the ditch;

Figure 3 is a view of the central part of the portable gate with the two sections of the dam stick being swung toward each other for folding the gate in a compact structure;

Figure 4 is a view showing the position the parts assume when the gate is folded;

Figure 5 is a sectional view showing the hinge connection between the two sections of the dam stick, said view being taken on the line 5—5 of Figure 1;

Figures 6 and 7 are sectional views taken on the lines 6—6 and 7—7, respectively, of Figure 3 showing the manner of connecting the adjusting links to the sections and also the manner of securing the flexible sheet material to said sections; and

2

Figure 8 is a view showing the pin for hinging the links together and connecting them to the adjusting post.

Referring to the drawings in detail, there is illustrated in Figures 1 and 2 the manner of use of our improved portable gate, indicated generally by the letter G. This gate has a frame structure F to which is attached a canvas sheet C or other suitable fabric or flexible sheeting. The gate is placed across a ditch D to dam up water flowing therein and keep it at the desired height. The frame structure is placed across the ditch from bank to bank and the canvas sheet C is held against the banks and bottom of the ditch by rocks or dirt piled thereon. The dammed up water in the ditch can then be directed into small lateral ditches between rows of plants and thereby accomplish efficient irrigation. A manner of conducting water from the dammed up water behind the gate can comprise syphon pipes P as shown in Figure 1, thus not necessitating cutting of the ditch bank.

The frame F of the portable gate embodying our invention is shown in detail in the various views and comprises two elongated members or arms 10 and 11. These may be of varying length, depending on the width of ditch to be dammed. Each member is made of metal and is of channel form in cross section, that is, U-shaped. The inner ends of the two elongated members are arranged to be hinged together by a double hinge joint. To accomplish this, there are provided two short links 12 and 13. A pivot pin 14 connects ends of these links to the member 10 and a pivot pin 15 connects the other ends of the links to the member 11. By means of these connecting links it is seen the elongated members can be arranged to have various angular relations and also, because of the double hinge arrangement, the members can be folded so they will be adjacent each other in substantially parallel arrangement.

The link 12 has secured thereto an adjusting post 16 which extends at right angles to the longitudinal axis of the link and in a direction upwardly with respect to the elongated members when they are positioned to extend across a ditch. The link 12 and post are made from one metal piece, or the post may be welded to the link. The post, at one longitudinal edge, is formed with notches 17 in spaced relation, said notches extending angularly upwardly into the body of the post from the post edge. A gripping handle 18 is provided at the top of the post. The post will be so related to the link 12 that a line extending through the base portions of

the notches will also pass through the center of link 12.

The frame structure F also has two adjusting links 19 and 20. These links are pivotally connected together by a pin 21 which extends at one end beyond the links and is formed with an enlarged head 22, all as best shown in Figure 8. The extended portion of the pin is for cooperation with the notches in the adjusting post, as will be apparent, and the head 22 will keep the pin from slipping out of a notch. The outer end of the adjusting link 19 is pivoted by a pin 23 to a bracket member 24 secured, as by welding, to one side of elongated member 10. The outer end of adjusting link 20 is pivoted by a pin 25 to a bracket member 26 secured, as by welding, to the top of the elongated member 11.

The adjusting links 19 and 20 are of like length and their connections with the members 10 and 11 are at points spaced from the hinge connection approximately their length. The adjusting links with the members will then produce a parallelogram arrangement, and when the pin 21 is placed in various notches 17 of the adjusting post, the angular relationship between the adjusting links and the elongated members can be varied. This will vary the angular relationship between the two elongated members from substantially 180 degrees to lesser angles. This will permit the central part of the gate, when in use, to have its height varied with respect to the top of the ditch banks and thereby control the height of the water which will be dammed up.

The channel form of the elongated members permits the attachment of the canvas sheet C of the gate in a convenient manner. The canvas sheet has its upper marginal edge turned back and stitched to the sheet to provide two tunnels 27 and 28. The inner ends of these tunnels are spaced apart so that the top central edge of the canvas will be free of attachment to the gate frame. A square wooden stick 29 is placed in the tunnel 27 and a like square wooden stick 30 is placed in tunnel 28. These sticks are approximately the lengths of the elongated members.

To attach the canvas to the elongated member 10 the stick 29, after being placed in the tunnel 27, will be positioned in the channel of said member and held therein by screws 31, which extend through holes in the top of the member. When the screws are drawn up, the marginal looped part of the canvas will be firmly clamped to the member. The stick 30 is similarly held by screws 32 in the channel of member 11, thereby clamping the canvas throughout tunnel 28 to the said member. It is believed to be apparent that the attaching means for the canvas permits quick and easy removal of an old worn out canvas and the replacement by a new canvas.

With our improved portable gate, it is believed to be obvious that a ditch can be dammed as desired to accomplish irrigation by lateral ditches. The amount of water to be dammed can be varied as desired by placing the connecting pin 21 of the adjusting links in different notches of the adjusting post. Due to the angular position of the notches, an adjusted position will be maintained as the hinged part of the frame structure is acted on by a downward force, thus tending to hold the pin in a notch. The frame F will be self positioning when the gate is operative, regardless of how slack the canvas is held in the ditch, due to the fact that the frame can "rock" on the ditch banks. When it is desired to transport or store the gate, the pin 21 can be removed

from a notch and then the elongated members 10 and 11 will be free to be folded into parallel relation, as shown in Figure 4. The double hinge permits full folding to the parallel relation and allows for some space therebetween for the folding of the adjusting links 19 and 20. When the frame is folded there will be no interference by the canvas due to the unattached section at the hinge. With the frame folded, the canvas can then be wrapped around the elongated members to make a compact arrangement permitting easy carrying on a person's shoulder or storage in a minimum of space. The simple and efficient manner of attaching the canvas to the elongated members permits quick and easy renewal of a canvas. Although tunnels are shown in which the sticks are inserted, these are not necessary for holding as a marginal edge of a canvas can be firmly secured by the clamping action involved without use of tunnels. The tunnels do, however, have the feature of causing the canvas to pull on the center line of the stick.

Being aware of the possibility of modifications in the structure disclosed without departing from the fundamental principles of our invention, we desire it to be understood that the scope of the invention is not to be limited except in the manner set forth by the appended claims.

What is claimed is:

1. In a portable ditch gate, a structure for placing across the ditch above the bottom thereof and resting on the opposite banks and for supporting a sheet of flexible material so that it can extend downwardly into an engageable relation with the bottom of the ditch and thus establish the gate and for also adjusting the height of the sheet, said structure comprising two rod-like elongated members to which the sheet of material is to be connected, means carried by the elongated members for attaching a marginal portion of the sheet thereto, means for hinging ends of the members together, the length of the members being such that when the members extend in opposite directions from the hinging means they can rest on the ditch banks, a post extending from the hinge connection so that it will extend upwardly when the members rest on the ditch bank and will be positioned adjacent the elongated members as they are swung toward each other, adjusting links, means for pivotally connecting ends of the links together in a permanent relation, means for pivotally connecting the other end of each link to a separate elongated member intermediate the ends thereof, and means for connecting the ends of the links which are pivotally connected together to the post at any of variously spaced points from the end at the hinge means, said links being of such length and said ends of the links which are pivoted together being capable of such movement and the ends of the elongated members being so hinged together that the elongated members can be caused to assume substantially parallel relation when the gate is to be stored or transported and when in such relation the pivotally connected ends will be in spaced relation to the end of the post remote from the hinge means.

2. In a portable ditch gate, a structure for placing across the ditch above the bottom thereof and resting on the opposite banks and for supporting a sheet of flexible material so that it can extend downwardly into an engageable relation with the bottom of the ditch and thus establish the gate and for also adjusting the

height of the sheet, said structure comprising two rod-like elongated members to which the sheet of material is to be connected, means carried by the elongated members for attaching a marginal portion of the sheet thereto, means for hinging ends of the members together including spaced pivot points, the length of the members being such that when the members extend in opposite directions from the hinging means they can rest on the ditch banks, a post extending from the hinge connection so that it will extend upwardly when the members rest on the ditch bank and will be positioned adjacent the elongated members as they are swung toward each other and toward the post, adjusting links, said post being of a length substantially less than either elongated member and said links being of lengths substantially the distance from a hinge pivot to the point of pivotal connection with an elongated member, means for pivotally connecting ends of the links together in a permanent relation, means for pivotally connecting

the other end of each link to a separate elongated member intermediate the ends thereof, and means for connecting the ends of the links which are pivotally connected together to the post at any of variously spaced points from the end at the hinge, said last named means including longitudinally spaced notches on the post and projecting means at the ends of the links which are connected together for reception in a selected notch.
